CLAIM

The ornamental design for a razor storage case, as shown and described.

DESCRIPTION

FIG. 1 is a front perspective view as seen from the top, front, and right side of a razor storage case showing our design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right elevational view thereof;

FIG. 7 is a left elevational view thereof; and,

FIG. 8 is a top plan view of the case laid open.

The broken lines in the drawings illustrate portions of the razor storage case and form no part of the claimed design.
